UNITED STATES PATENT OFFICE.

WILLIAM BERGNER, OF BALTIMORE, MARYLAND.

DESIGN FOR AN EASEL-STAND.

SPECIFICATION forming part of Design No. 25,758, dated July 7, 1896.

Application filed March 23, 1896. Serial No. 585,288. Term of patent 8½ years.

To all whom it may concern:

Be it known that I, WILLIAM BERGNER, a citizen of the United States, residing in the city of Baltimore, State of Maryland, have 5 invented a new and original Design for Easel-Stands, of which the following is a specification, reference being had to the accompanying drawing, which is a perspective view of my easel-stand.

10 The leading feature of my design consists of the base of the easel having rounded pillows on each end, the center being raised above the lower level of the pillows and having a drawer inserted in the center portion 15 and suspended between the pillows. Secured to the bed is a rest-block and a rest-bar, which is rounded at the top and extends upward in an inclined position. The rest-block is set back from the front edge of the bed a short 20 distance.

A is the bed, having rounded ends a' a', which form pillows upon which the bed rests.

A² is the center of the bed, raised above the surface upon which the pillows rest.

a³ is a drawer adapted to hold loose photographs and inserted in the center a² of the bed and suspended therein between the pillows a' a'. The face of the bed and its sides are variously ornamented.

B is a rest-block located upon the front 30 edge of the bed, but about one-quarter of an inch back from the edge. It is triangular in shape and its rest-surface is at right angles to the rest-bar.

What I claim and desire to secure is-- 35
The design for an easel-stand substantially as shown and described.

WILLIAM BERGNER.
